UNITED STATES PATENT OFFICE.

ELBRIDGE S. HAINES, OF ST. JOHN, NEW BRUNSWICK, CANADA.

SAWING-MACHINE.

1,023,079.

Specification of Letters Patent.

Patented Apr. 9, 1912.

Application filed August 7, 1911. Serial No. 642,852.

To all whom it may concern:

Be it known that I, ELBRIDGE S. HAINES, of the city of St. John, in the Province of New Brunswick and Dominion of Canada, **5** have invented certain new and useful Improvements in Sawing-Machines, of which the following is a full, clear, and exact description.

This invention relates to improvements **10** in sawing machines, and the object is to provide means for sawing off the submerged tops of piles or the like.

The device consists briefly of a pair of pivoted side members held in parallel relation by links pivoted thereto. A horizontal saw frame is mounted at the lower ends of the side members, means being provided to keep said saw frame always in the same horizontal plane, during the oscillation of **20** the side members. A suitable frame-work is provided to support the side members, said frame-work being provided with a rack and pinion mechanism for feeding the saw.

25 In the drawings which illustrate this invention:—Figure 1 is a front elevation of the device. Fig. 2 is a side elevation of the same. Fig. 3 is a perspective view of the lower end of the device showing the arrangement of the saw frame. Fig. 4 is a horizontal section on the line 4—4 of Fig. 1. Fig. 5 is a vertical section on the line 5—5 of Fig. 1, showing the resilient mounting of the saw frame.

35 Referring to the drawings, 6 designates a foundation member of suitable shape such as the angle shown in the drawings. The foundation is slotted or otherwise prepared at 7 to receive a pair of vertical tubes 8, **40** which are connected thereto by brackets 9 having set screws 10 engaging any one of a series of apertures 11, formed at regular intervals in the tubes 8. The lower ends of the tubes 8 are fixed to a small casing 12 **45** which holds the tubes in parallel relation. Passing through each tube and through the casing 12 is a rod 13, pointed at the lower end 14. These rods are of such length that they may be driven downwardly to engage **50** submerged ground, and thus anchor the lower end of the tubes 8, the upper ends being anchored by fixing the foundation 6 wherever desired. A pair of posts 15 are rigidly attached to the foundation 6, a short **55** distance away from the tubes 8. Pivots mounted on these posts 15 are a pair of tu-

bular side members 16, built up of sections of pipe 17, connected together by means of T's 18. The particular sections 17^a which engage the posts 15 are provided with a series of regularly spaced apertures 19, through which the posts pass. The central arms of the T's 18 are turned rearwardly, *i. e.*, to face the foundation 6, and to these central arms, links 20 are pivotally connected. These links are all of equal length and therefore hold the side members 16 parallel, but at the same time, allow them to oscillate freely from side to side, as indicated in dotted lines Fig. 1. At the point **60** where the members 16 are pivotally supported on the posts 15, an additional link 21 is provided, having bifurcated ends 22 which embrace the members 16, and are at the same time held in place by the posts 15. **65** A second link 23 similar to the link 21 is provided near the lower extremities of the side members. The bifurcations 24 of this link carry posts 25 which pass through slots 26 in the side members, in order that they **70** may move vertically with respect to the side members. These posts 25 project some distance forwardly of the side members, and carry a saw 27, held in tension between them. A pair of racks 28 are provided, **75** extending rearwardly at right angles to the links 21 and 23. The lower of these racks is connected to the link 23 in such a manner that the link will slide freely through the rack in a transverse direction. **80** A vertical shaft 29 journaled to the foundation 6 and to the casing 12 is located midway between the tubes 8. Small pinions 30 are mounted on this shaft in position to engage the racks 28, the lower pinion being **85** located within the casing 12, so as to be protected from floating objects. It will be seen in the drawings that the lower link 23 is in the same horizontal plane with the casing 12, and is permanently maintained in this **90** plane by passing through slots 31, formed in posts 32, projecting forwardly from the casing 12. A small hand wheel 33 is provided to rotate the rod 29. The lower ends of the members 16 are closed by caps 34, **95** and a short distance above the slots 26, the bore of the members is blocked by a plug 35. The portion of each saw post 25 which passes through the side member is provided with a small block 36, arranged to **100** slide within the member. Helical springs 37 are located within the members 16, be-

tween the block 36, plug 35 and cap 34. Operating ropes or chains 38 may be attached at any suitable point to the members 16. The racks 28 are held in engagement 5 with their respective pinions 30, either by means of the slots 39 through which they pass in the casing 12 and foundation 6, or by means of rollers, springs, or other suitable devices not shown.

10 The operation of the device is quite simple. The foundation 6 is secured to a wharf, interior of a caisson or other desired point. Fine adjustments of height to bring the saw to the proper level are made by means of 15 the apertures 11 or 19. The rods 13 are then driven downwardly until their points 14 engage the river or sea bed, so as to firmly anchor the bottom of the tubes 8, the top being obviously anchored by the 20 foundation 6. By pulling the ropes 38 alternately, the side members 16 will be oscillated as shown in dotted lines Fig. 1, the links 20 holding said members always parallel. This oscillation naturally causes the 25 reciprocating motion of the saw 27, so that the same will readily cut off the top of a pile or other object against which it is pressed. As the members 16 are pivoted at fixed 30 points, there is bound to be a certain rise and fall of the saw posts 25, carried at their lower ends if these posts were fixed, which would cause the saw to bind, and make the operation extremely difficult or impossible. This rise and fall is overcome by passing 35 the posts through the slots 26, and connecting them through the medium of the link 23. This link reciprocates through the slots 31 of the fixed posts 32, and is thereby maintained in the same horizontal plane, thus 40 holding the posts 25 in this plane so that they move up and down in the slots 26, relatively to the members 16. The saw is fed forward as it cuts by means of the wheel 33, which rotates the pinions 30 and reciprocates the racks 28. These racks being located approximately at the top and bottom 45 of the members 16, keep the same in a substantially vertical position, so that the saw is not inclined by the feeding and is therefore not liable to bind. Since the position 50 of the rack 28 is fixed as regards lateral motion, it is necessary that the link 23 should slide therethrough, as previously stated.

55 The entire device may be constructed of pipe, pipe fittings, and other standard shapes, so that the cost will be comparatively small. The machine is very compact and may be readily used within caissons or in other cramped quarters. If the sawing to 60 be done is very much below water level, additional sections of pipe may be inserted in the members 16 and 8, the anchors 13 and feeding shaft 29 being correspondingly lengthened. The saw moves always in the 65 same plane and is therefore prevented from

binding, so that the device may be very easily operated by the minimum number of workmen. For shipment, the machine may be quickly and readily dismounted and packed in a very small space.

Having thus described my invention, I declare that what I claim is:—

1. In a device of the class described, a supporting framework secured at top and bottom, an oscillating framework pivotally mounted thereon, a saw carried at the lower end of said oscillating framework, and means for holding the saw in one horizontal plane during the oscillation of the framework. 70

2. In a device of the class described, a supporting framework fixed at the top and bottom, an oscillating framework pivotally mounted thereon, a saw mounted at the lower end of said oscillating framework, 75 said saw operating laterally, and means for preventing rise and fall of said saw, due to the oscillatory motion of the framework. 80

3. In a device of the class described, a supporting framework fixed at the top, adjustable stakes anchoring the bottom of said supporting framework, an oscillating framework pivotally mounted on the supporting framework, and a horizontally operating saw mounted at the lower end of said oscillating framework. 90

4. In a device of the class described, a foundation member, a pair of vertical tubes adjustably secured thereto, stakes vertically adjustable within said tubes to anchor the 100 lower ends thereof, an oscillating framework pivotally mounted on the foundation, a saw moving in a horizontal plane, operated by said framework, and means for shifting said oscillating framework to feed the saw. 105

5. In a device of the class described, a supporting framework rigidly mounted at the top and bottom, a framework pivoted thereto and arranged to oscillate in a vertical plane, a saw mounted at the lower end of 110 said latter framework arranged to operate in a horizontal plane, means carried by the supporting framework for maintaining the saw in a single horizontal plane during the oscillation of the pivoted framework, and means for shifting the pivoted framework 115 from one vertical plane to another to feed the saw.

6. In a device of the class described, a supporting framework secured at top and 120 bottom, a second framework comprising a pair of parallel side members, pivotally mounted on said supporting framework, links pivotally connecting said side members and maintaining the same in parallel 125 relation, a saw mounted at the lower end of said framework, and means for oscillating said pivoted framework, and means for shifting the same to feed the saw.

7. In a device of the class described com- 130

prising a foundation member, a pair of vertical tubes, means for adjustably securing the upper end of the tubes to said foundation, stakes passing through said tubes arranged to be driven into the ground whereby the lower end of the tube will be secured, an oscillating framework pivoted to the foundation, a saw mounted at the lower end thereof, and means for shifting said oscillating framework to feed the saw.

8. In a device of the class described comprising a foundation member, a pair of vertical tubes, means for adjustably securing the upper end of the tubes to said foundation, stakes passing through said tubes arranged to be driven into the ground whereby the lower end of the tube will be secured, a framework pivoted to the foundation and arranged to oscillate in a vertical plane, a saw mounted at the lower end of said framework arranged to operate in a horizontal plane, and means for maintaining the saw in the same horizontal plane during the oscillation of the framework.

25 9. In a device of the class described comprising a foundation member, a pair of vertical tubes, means for adjustably securing the upper end of the tubes to said foundation, stakes passing through said tubes arranged to be driven into the ground whereby the lower end of the tube will be secured, a framework pivotally mounted to the foundation and arranged to oscillate in a vertical plane, a saw frame slidably mounted at

the lower end of said oscillating framework, 35 a saw carried by the saw frame operating in a horizontal plane, means mounted on the vertical tubes engaging the saw frame to maintain the saw in one horizontal plane during the oscillation of the framework, 40 and means for shifting said oscillating framework to feed the saw.

10. In a device of the class described comprising a foundation member, a pair of vertical tubes, means for adjustably securing 45 the upper end of the tubes to said foundation, stakes passing through said tubes arranged to be driven into the ground whereby the lower end of the tube will be secured, a framework pivoted to the foundation and arranged to oscillate in a vertical plane, a saw frame slidably mounted at the lower end of said oscillating framework, a saw carried by the saw frame operating in a horizontal plane, slotted posts carried by 50 the vertical tubes through which the saw frame is reciprocated by the oscillation of the pivoted framework, springs within the framework above and below the saw frame, and rack and pinion mechanism arranged to 55 shift the pivoted frame with respect to the foundation whereby the saw is fed.

In witness whereof I have hereunto set my hand in the presence of two witnesses.

ELBRIDGE S. HAINES.
